UNITED STATES PATENT OFFICE.

RICHARD S. AYRES, OF BROOKLINE, MASSACHUSETTS.

MANUFACTURE OF BOOT AND SHOE HEELS.

1,327,851.

Specification of Letters Patent. Patented Jan. 13, 1920.

Application filed October 18, 1916. Serial No. 126,425.

To all whom it may concern:

Be it known that I, RICHARD S. AYRES, a citizen of the United States, and resident of Brookline, in the county of Norfolk and State of Massachusetts, have invented an Improvement in the Manufacture of Boot and Shoe Heels, of which the following description, in connection with the accompanying drawings, is a specification, like letters on the drawings representing like parts.

My present invention relates to the manufacture of boot and shoe heels from pulp material, and the object of the invention is a simple, practicable and economical process or method of manufacturing such heels.

In my prior application, Ser. No. 31,865, filed June 3, 1915, now Patent Number 1,270,586, of June 25, 1918, describing my improved heel of a suitable pulp material, some of the important advantages incident to the use of such an integral molded heel for boots and shoes are fully explained, greatly simplifying, cheapening and expediting the manufacture of boots and shoes.

Such a heel consists essentially of a mass of pulp material such as leather scraps, leather-board scraps, paper, jute, hemp, cotton stocks, wood pulp or the like, beaten up and preferably mixed with a suitable binder and then molded and compressed into substantially the form of a finished shoe heel, either with or without a solid leather toplift, which heel is light, strong, easily attached and capable of taking blacking, stain or other finish to match with the upper material of the shoe. In the efforts to handle such a mass of pulp, however, and to shape it, mold and compress it, great difficulty has been experienced. The pulp material must

necessarily be beaten up in a considerable mass, together with a great quantity of water or other solvent and numerous processes have been tried in the effort to take a proper mass of such pulp, eliminate the water, transfer same to molding appliances, whether for hand or machine operation, and to suitably compress and mold it. The pulp handling art has been heretofore developed to make and handle only such pulp into sheets or boards ranging from thin paper sheets to heaviest leather boards, which could be run through continuous carriers for the elimination of the water, or by dipping molds into a mass of pulp. No prior process was suitable or possible in the taking up and manipulation of such large masses

of pulp in predetermined extent for subsequent compression and molding into a shoe heel and it is the object of my present invention to accomplish this work. It will be appreciated that the handling of a considerable mass of pulp material from the beater to and through successive drying, conveying, molding and compressing devices presents a highly difficult problem. While the pulp is in its moist and beaten up state in the beater, it is extremely sticky and difficult to handle, while it is also practically impossible to subject as large a mass of pulp as must be handled for subsequent compression into a heel, until the water or moisture is eliminated. In order to make a practicable, non-laminated and integral heel it is essential that extremely heavy pressure be applied, compressing, unifying, and solidifying the entire mass and the prior process of running pulp through successive pairs of rolls for this work, are, of course, impossible in heel molding.

My process consists, essentially, in first beating up the pulp, from any suitable pulp material, to which a binder may be added when desired; then to take a mass of pulp from the beater and roughly shape or mold the same, thus having a predetermined mass for subsequent compression into the desired sized heel; this first shaped mass is then subjected to suitable drying processes, either through direct exposure in the air or by means of a hot air current; then when suitably dried, so that the final compression will not show any further moisture, the mass is subjected to very heavy compression in suitable molds to impart the substantially finished shape to the heel. In such instances I may attach a solid leather toplift to the heel after it is dried and just before subjecting the roughly shaped heel and toplift to the final compression;—or where the final compression would be so heavy as to injure the solid leather toplift, the latter would be attached after the heel is otherwise molded into final shape. While it is desirable to use a solid leather toplift in ordinary instances, I contemplate the solidifying and compressing of the pulp heel to a suitable extent so that the bottom surface of the pulp heel itself will be sufficiently wear-resisting to enable the completed heel to be used without a toplift.

While my process may be carried out either by hand or machines, I have illus-

trated in the machine of the drawings an apparatus which is suitable for carrying out my process.

Referring to the drawings,

5 Figure 1 is a front view of an apparatus suitable for use in the manufacture of pulp heels according to my process;

Fig. 2 is an enlarged detail view of an intermittent driving mechanism;

10 Fig. 3 is a side view of the apparatus; and

Figs. 4 and 5 are enlarged plan and elevation views of a heel mold.

In carrying out the process I have illustrated an apparatus with substantially automatic pulp handling, shaping, drying, compressing and discharging means, assembled in suitable relation for the proper sequence of operations of the process.

20 The machine comprises a vertical support 1 carrying a rotatable work-holding table 2 resting on a collar 3 secured to the support and with a pair of brackets 4 and 5 at diametrically opposite points on the upper part of 25 the machine and at right angles thereto a corresponding pair of brackets or arms 6 and 7. The bracket arm 4 consists in a framework having an upper member 8 supporting bearings 9 and 10 for a horizontal

30 shaft 11 and a lower horizontal extending member 12 carrying bearings for a cam wheel 13. The upper and lower portions 8 and 12 are further united by a brace 14 and have clamping arms 15 and 16 at top and 35 bottom respectively to support the receiving tank 17. This tank is intended to receive a mass of pulp after it has been suitably beaten up and mixed either with the addition of a binder or without. This tank also

40 has a feeding and stirring device consisting in a central shaft carrying blades 19 as illustrated in dotted lines Fig. 1, rotation of the said shaft being imparted by a bevel wheel 20 at the upper end, meshing with a 45 correspondingly beveled wheel 21 on the end of the shaft 11. This serves to keep the pulp material suitably stirred up and to press and feed the same downwardly into a gate or opening through the supporting bracket 50 16 and into a preliminary mold or press 22.

To open and close the gate to the mold 22 and to impart a preliminary shaping or molding to the mass of pulp material, as well as to separate from the pulp a suitable amount for subsequent compression, I 55 provide an intermittent feeding and compressing mechanism, consisting in a rod 23 having at its outer end a cam roll 24 to engage the cam groove 25 within the wheel 13,

60 said rod operating a gate plunger 26. Reciprocation of the rod 23 caused by rotation of the cam wheel 13 will move the plunger to and fro within the mold 22, its upper part automatically permitting a predetermined 65 mass of pulp to be forced into the mold by

the blades 19 and then to automatically shut off same and partially compress the mass of pulp thus segregated. I prefer to arrange an adjustable connection between the rod 23 and the plunger 26, as for example by 70 means of a headed bolt 27 which may be adjusted throughout the limit afforded by the length of a slot 28 in the plunger and thus to determine the amount of pulp to be subsequently compressed. A discharge chute 29 75 leading to the bottom of the mold 22 and supported by an arm 30 is also provided to conduct the molded mass downwardly into a drying and compressing mold mounted on the worktable 2 which worktable will be 80 rotated in timed relation to the operation of the cam wheel 13 so as to receive a partly molded heel from the mold 22. To operate the cam wheel 13 I provide at one end of the shaft carrying same a pulley (not shown) 85 receiving power through a sprocket chain conventionally indicated at 31 from a pulley 32 mounted on a shaft 33 carried at the upper portion of the frame 8, and receiving rotation through a gear wheel 34 from a 90 worm 35 keyed on the shaft 11.

The molded mass of pulp, thus compressed, is delivered to a suitable second mold mounted on a worktable 2, and which is in position underneath the chute 29 to receive the heel blank when delivered therefrom. The worktable 22 will be given an intermittent rotative movement and will carry a large number of heel molds, so that the operation of the apparatus will be continuous. Rotation of the table 2 will, eventually, bring the heel blank delivered from the chute 29 around into position under a press or plunger 36. During this movement the heel blank will be further dried and the 100 water or moisture contained therein evaporated. I may also desire to conduct the heel blank through a drying chamber or tunnel to receive a blast of air or heated air, to complete the drying before the final compression of the blank. I have indicated at 105 37, Fig. 3, in conventional outline a drying tunnel receiving a blast of air or heated air through a support and pipe 38 connected to a blower or any suitable draft creating appliance. The blank is then brought under the plunger 36 for final compressive action.

To actuate the plunger 36, I mount the same on a stem 39 which is adjustably secured to a slide 40, by a set screw 41, which 120 slide is arranged to reciprocate in a bearing through the lug 42 carried by the bracket 5. A link 43 is pivoted at 44 to the upper end of the slide 40 and has its other end adjustably secured at 45 to an undercut 125 groove 46 in a disk 47, said disk being carried by a shaft 48 mounted in bearings 50, 51, carried on the brace 52, at the upper end of the standard 1 and directly opposite the bracket 4. The shaft 11 has a beveled 130

gear 53 at its inner end and the shaft 48 has a similar beveled wheel 54 on its inner end, both these gears being arranged to mesh with a horizontal gear 55 carried on a 5 vertical shaft 56 journaled within the standard 1, which latter is formed hollow for this purpose. Rotation of the gear 55 thus actuates the shaft 11 and the various instrumentalities associated therewith and also 10 the plunger 36.

I prefer to rotate the gear 55 by a beveled gear 57, shown in dotted lines in Fig. 1, which meshes therewith at right angles to the position occupied by the gear 53 and 54 15 as shown in Fig. 3. The gear 57 is carried by a shaft 58 mounted in suitable bearings on the bracket 6 and having at its outer end a pulley 59 belted to a pulley 60 near the base of the apparatus by a belt 61, which 20 lower pulley 60 is carried on a shaft 62 in bearings at the base of the machine, and has a power-receiving pulley 63 which may be connected with any source of power. Diametrically opposite the shaft 58 and 25 carried on the bracket 7 is a corresponding shaft 64 having a beveled gear 65 also shown in dotted lines, Fig. 1, and receiving power from the horizontal gear 55. The shaft 54 carries a gear 66 meshing with a horizontal 30 gear 67 mounted in a lug 68 on the bracket 7 and having keyed on its shaft one of a pair of intermittent gears 69 and 70. These 35 gears are shown in enlarged plan view in Fig. 2. The gear 70 is secured to a vertical shaft 71 having at its lower end a gear wheel 72 with its teeth arranged to mesh with corresponding teeth in the periphery of the table 2, so that the worktable 2 will be given a step-by-step or intermittent 40 rotation movement timed and controlled by the gears 69 and 70. This step-by-step movement is preferably sufficient to permit a halting of the worktable 2 under the chute 29, to receive a heel blank, and under the 45 plunger 36 to enable the heel blank to receive its final compressive action.

It will be appreciated that the gears 69 and 70 may be timed as desired and the speed of rotation of these gears may be reduced to appropriate extent by the intermediate actuating gears 66 and 67. The driving gear 69 has its periphery solid for a portion of its circumference, as indicated at 74, on a circle shorter than that of its 55 teeth, and the driven gear 70 has a proportional part of its circumference formed in a concave arc as shown at 75 to fit the circumference 74 of the driving gear. The gears are thus meshed and when the gear teeth 60 are in engagement, a partial rotative movement is imparted to the driven gear 70, while, when the uncut portions 74 and 75 are in mesh, the driven gear 70 is not rotated and in fact is held and locked against rotation until the entire sector 74 has moved 65

past the concave part 75. The wheel 69 is thereby permitted to be in continuous rotative movement while the gear 70 is intermittently rotated.

In order to receive the heel blank from the chute 29 and to enable it to be carried, dried and subsequently compressed under the plunger 36, I have provided a novel form of blank-receiving molds, illustrated in Figs. 4 and 5. These molds comprise a pair of sections 76 and 77 having rearwardly extending arms 78 and 79 respectively which are pivoted at 80. These sections may be of any suitable contour to aid in imparting the desired shape to the compressed heel and 75 preferably are open at the bottom and may also be perforated at the sides, as indicated at 81, 81, to facilitate the evaporation of the moisture therefrom. The pivot 80 may also extend downwardly into the table 2 to hold 80 the molds in proper position. The heel blank being delivered into the mold-receiving space 82 is dried while the table 2 is moved step-by-step, additional drying being given while the mold passes through 85 the tunnel 37 until the mold and its contained blank arrive under the plunger 36, when a further compressive action is imparted to the heel, while the worktable 2 is 90 stationary and locked in position by the intermittent gears 69 and 70. The next movement of the worktable moves the completely 95 compressed blank out from under the plunger 36 and moves another mold and blank under the plunger 36. The completely 100 compressed blank is then, preferably, automatically ejected from the mold, and I also prefer to open the molds automatically for this purpose. In order to automatically 105 open the molds I swing the same on the pivot 105 80 by means of a slide lever secured at 84 to the lower part of the table 2 and having a bolt 85 passing through a suitable slot in the table 2 and engaging the ends of links 86 and 87 pivoted to the extreme end portions of 110 the arms 79 and 78 respectively (see Fig. 4). A portion of the lever 83 has an inclined face as shown at 88 and a post or trigger 89 supported by a brace 90 secured to the standard 1 is arranged in position to 115 bear against the beveled face 88 of the slide 83 during the rotation of the worktable 2. This action moves the slide 83 and bolt 85 to the rear, viewing Figs. 1 and 4, and thus opens the mold sections 76 and 77, freeing 120 the blank therefrom. A spring (not shown) will return the slide 83 to normal position and consequently close the molds in time for the same to receive the next blank as the mold arrives under the chute 29. 125

In handling a mass of pulp material such as shoe heels, it is often difficult to start the same from a mold and even the opening of the mold sections will not always free the heel therefrom, as it is apt to adhere to one 130

side or the other of the mold sections. Therefore I provide automatic mechanism to forcibly eject the heel blank from the mold; throwing it upwardly with sufficient 5 impetus to force the heel entirely out of the mold and to free it from either section should the heel adhere to the sides of one when the molds are opened. To this end I have arranged a vertically reciprocating 10 rod 91 adapted to be actuated upwardly through an aperture in the worktable 2 under each pair of molds. This rod 91 has a stud 92 at its lower end in position to engage a cam path 93 cut in a cam wheel 94, which 15 wheel is mounted on a shaft having its other end provided with a beveled gear 95 adapted to be driven in any suitable manner by geared connections from the main shaft 62. Rotation of the cam wheel 94 is suitably 20 timed so as to throw the rod 91 upwardly and downwardly during the intermittent stopping of the worktable 2 when the molds are successively in alignment with said rod 91. A part of the support or frame 96 is 25 extended upwardly to a slide bearing 97 for the rod 91, as clearly shown in Fig. 1. In order to aid the worktable 2 in withstanding the pressure applied by the plunger 36 I have mounted a roller 98 in a bracket 99 at 30 the front of the machine in position under the worktable 2. As a further support for the shaft 71, I also extend a bracket 100 supporting, at its outer end, a block 101 as a support and bearing for the adjacent end 35 of the shaft 71.

The operation of the apparatus has been described in the foregoing, and my process of pulp heel manufacture may be advantageously carried out therewith.

40 The pulp material being mixed in a beater engine is poured into the receiver 17, or the pulp material may itself be mixed in said receiver, but preferably a large mass is beaten up and then the receiver 17 filled from time to time. The pulp is kept beaten 45 up and forced downwardly, being positively fed through the gate of the receiving tank 17 when the member 26 permits the same, as already explained, and a separated mass of 50 pulp material is given its preliminary shape therein and delivered into the mold. This preliminary molding serves to force out a large amount of the moisture or liquid in a pulp mass, and the heel blank is further dried before it is again compressed into its 55 substantially finished form by the plunger 36. It will be appreciated that even after this final compression, the heel can be 60 trimmed in the same manner as a leather heel, to have it conform still further to a style or size of shoe in which it is incorporated, but I gain considerable advantages in shaping the heel at once to its final form by having appropriately formed molds therefor.

While I prefer to separate a mass of the 65 pulp material directly from the tank 17 as herein explained, the invention also contemplates a slightly modified form in the process, which would consist in forcing out the pulp material from the tank 17 through a 70 die which would give the form to two sides of the heel blank as well as the top and bottom, which material would be subsequently 75 cut into proper lengths for each individual heel. This involves the preliminary shaping of the pulp mass and then a cutting of the mass so shaped into heel blanks in 80 contra-distinction to the method illustrated by the machine of the drawings, which consists in simultaneously separating and forming 85 the individual heel blank from the mass of pulp; all subsequent operations being identical.

My invention is further described and defined in the form of claims as follows:

1. The process of making integral molded boot or shoe heels which consists first in preparing a mass of fibrous pulp material, then separating from said mass a predetermined amount, suitable for subsequent compression into the sized and shaped heel to be produced, giving to said predetermined mass a preliminary compressing and shaping, then drying said heel blank by removal of substantially all moisture therefrom, and finally molding, compressing and solidifying said heel blank into the desired finished shape and size.

2. The improved process of making integral molded boot or shoe heels which consists first in preparing a mass of pulp material, then separating from said mass a predetermined amount of pulp material and subjecting it to a preliminary molding and shaping, eliminating a portion of the water thereby, then air-drying said blank and then subjecting it to a final solidifying, compressing and shaping action by a relatively heavy pressure.

3. The improved process of making integral molded boot or shoe heels which consists first in preparing a mass of pulp material, then separating from said mass a predetermined amount of pulp material and subjecting it to a preliminary molding and shaping, eliminating a portion of the water thereby, then air-drying said blank, then adding a leather toplift, and then subjecting said heel, including the top-lift, to a final solidifying, compressing and shaping action by a relatively heavy pressure.

In testimony whereof I have signed my name to this specification in the presence of two subscribing witnesses.

RICHARD S. AYRES.
